UNITED STATES PATENT OFFICE.

ALBERT WEHMEIER, OF ST. LOUIS, MISSOURI, ASSIGNOR TO FORE ELECTRICAL MFG. CO.,
A CORPORATION OF MISSOURI.

RECTIFIER.

1,247,759.

Specification of Letters Patent. Patented Nov. 27, 1917.

Application filed August 16, 1916. Serial No. 115,170.

To all whom it may concern:

Be it known that I, ALBERT WEHMEIER, a citizen of the United States, residing at the city of St. Louis, State of Missouri, have 5 invented a certain new and useful Improvement in Rectifiers, of which the following is a full, clear, and exact description, such as will enable others skilled in the art to which it appertains to make and use the same, reference being had to the accompanying drawings, forming part of this specification.

This invention relates to certain improvements in a mechanical rectifying device for deriving from an alternating current a direct form of current suitable for the charging of storage batteries and the like.

The general purpose of my invention is to provide a simple, compact and economical form of rectifying device which may be used 20 in connection with the form of alternating current commonly supplied to consumers by commercial plants, and which may be conveniently, safely and successfully operated by individuals not necessarily conversant 25 with the principles of electricity involved.

A more specific object of my invention is to improve intensively upon the vibratory form of rectifier for the purpose of rendering the operation of the device more positive, certain and uniform, and less subject 30 to the influence of variations in the potential of the impressed current.

Other and further objects of the invention will be obvious or pointed out hereinafter.

35 In the accompanying drawing, I have shown diagrammatically an assembly of parts embodying my improvements.

In various forms of vibratory rectifiers known to the art, the vibrator, which operates as a switch, is operated by the impressed alternating current to open and close the contacts which it controls in such fashion that current impulses of the selected sign only, are allowed to pass to the outlet terminals. In these devices the vibrator or vibratory switch is operated directly by magnetic influences derived from the impressed current.

50 In my improved device, I operate the vibratory switch by a permanent magnet, the effectiveness of which upon the vibrator is governed by the impressed current, but the magnetic quality of which is not influenced by the impressed current.

In this fashion, the operation of the vibrator switch is rendered independent of variations in the potential of the impressed current, with the result that a more uniform and certain operation is insured, and the necessity for adjustment of the vibrator 55 switch is obviated. These, of course, are very desirable features in a device of this kind which is designed for use by comparatively inexperienced persons.

By reference to the accompanying drawing, let it be understood that 1 indicates the primary coil of the transformer, and 2 the secondary coil. The primary coil, of course, is equipped with suitable terminals whereby it may be connected in the supply circuit 60 carrying an alternating current. By suitable proportioning of the primary and secondary coils, the potential of the derived current may be suitably predetermined in the conventional fashion.

The numeral 4 designates a permanent magnet of horseshoe type having the positive or north pole N, and the negative or south pole S. I connect or bridge the poles of the permanent magnet with the permanent armature 5 of suitable magnetic material, upon which is wound a neutralizing coil 6. At 7 is flexibly mounted the vibratory switch member which includes the vibrating armature 8 arranged for magnetic 70 co-operation with the permanent magnet, and the contact carrying spring 9, the said switch being spring-pressed in such fashion as to normally hold the movable contact 10 out of electrical connection with the stationary 75 contact 11. Suitable connections with the

outlet terminals 12 and 14 are made respectively from the stationary contact 11 and the secondary coil 2, the former connection leading through a suitable fuse 15 and indicating ammeter 16. Likewise, a suitable connection 17 completes the circuit from the secondary coil 2 to the vibratory switch member. The neutralizing coil 6 is connected in shunt across the secondary coil circuit, a suitable non-inductive resistance 18 being included in the shunt circuit at the negative side of the coil. A suitable resistance 19 is also disposed in the connection to the negative terminal 14.

With the parts thus disposed, the permanent armature 5 forms a permanent magnetic bridge across the poles of the perma-

5 nent magnet 4, providing a normal path for the magnetic lines of force between the poles. Accordingly, so long as this path remains unimpeded, the lines of force of the permanent magnet will follow it, so that there will not be a sufficient field about the 10 vibrating armature 8 to render the magnet effective to close the movable contact 10 upon stationary contact 11 against the tendency of the vibrator spring. With the parts in this position there can be, of course, no supply of current to the outlet terminals 12 and 14. However, whenever the magnetic path provided by the permanent armature 5 is impeded, so as to prevent the normal flux of the permanent magnet therein, the field of the permanent magnet will be thrown out in the conventional form, and will comprehend the vibrating armature 8 within sufficient 20 of its lines of force to attract the movable switch with sufficient power to overcome the tendency of the spring and close the movable contact 10 upon the stationary contact 11. With the parts in such position, of course, the circuit is closed for the flow of current from the secondary coil to the terminals 12 and 14. The neutralizing coil 6 is the immediate means which I provide for neutralizing the permanent armature 5 so as to destroy its efficacy as a path for the magnetic lines of force of the permanent magnet. Accordingly, this coil 6 is so wound on the permanent armature 5 as to induce therein, when energized by 30 a current impulse of a predetermined sign, a magnetism which is counter in direction to the normal direction of the lines of force of the permanent magnet therein. Inasmuch as the sole purpose of the neutralizing coil 6 is to induce only enough counter magnetism in permanent armature 5 to overcome the power of the permanent magnet therein, the neutralizing coil need be only a very small one, and it is desirable that it 40 be as small as possible in order that it may have no other effect upon the permanent magnet or the vibratory switch member.

In the operation of the device, a suitable translating device, such as the storage battery B, being connected across the terminals 12 and 14, the primary current of alternating form is rendered effective in primary coil 1 so that a secondary current of the desired potential is induced in the secondary coil 2. This secondary current will, of course, be of alternating form, so that there will be a continuous reversal of direction of the current in neutralizing coil 6. In the arrangement illustrated, when the current is 50 of positive sign, the neutralizing coil will be effective to neutralize permanent armature 5, with the result that the north pole of the permanent magnet will be effective upon the vibratory member to close the switch. 55 As a result, a current impulse of positive

sign will be impressed upon the battery. As soon as the current of positive sign drops to the point where coil 6 is no longer effective to neutralize permanent armature 5, the field of the permanent magnet will be 70 altered so that the vibratory member will be released to open the switch. Accordingly, when the current assumes the reverse sign, the circuit to the battery will be opened and no impulse will be impressed upon the battery. It will be seen that, with the continuation of this operation, the battery will 75 always receive current impulses of the same sign, with the result that its potential will be gradually built up.

80 Numerous advantages accrue from this construction. In the first place, the force which operates the vibratory switch will always be constant, being represented by the magnetic intensity of the field of the permanent magnet. Hence there will be no necessity for adjustments of the switch contacts to accommodate changes in potential in the impressed current, and the possibility of irregular operation of the vibratory 85 member, and welding of the contacts, is greatly reduced. The intensity of the permanent magnet is maintained by the presence of the permanent armature 5 which, of course, normally forms a path for the magnetic circuit. The operation of the vibratory switch is immediate because of the fact that a permanent magnetic force is used, and, instead of requiring the generation of the necessary magnetism each time the 90 switch is closed, it is necessary simply to change the path of the permanent magnetic circuit, which is accomplished without appreciable loss, due to the smallness of the neutralizing coil. Hence a maximum 95 amount of each current impulse of the selected sign is impressed upon the battery.

100 In the arrangement shown, only the current of positive sign will be impressed upon the translating device, but it is obvious that 105 by transposing the poles of the magnet, the device may be arranged to select only the current of negative sign, and that by the provision of a second switch arranged for operation in alternation with the vibratory 110 member shown, the alternating current may be separated into separate circuits of opposite but each of constant sign for supply to separate translating devices.

115 I am also aware that the structure is 120 susceptible of other modifications and changes in detail, without departing from the scope of the invention involved.

125 What I claim is:

1. A device for the rectification of electric currents including a permanent magnet, a permanent armature forming a metallic connection between the poles of the magnet, a switch device including a vibratory circuit making and breaking member arranged for 130

magnetic coöperation with the said magnet, a source of alternating current supply, and means associated with the permanent armature and with said source of supply for diverting the magnetic circuit of the permanent magnet in accordance with the direction of the impressed current.

2. In a current rectifying device, a source of alternating current supply, a circuit therefor, a vibratory switch device arranged to open and close said circuit, a permanent magnet disposed for magnetic coöperation with said vibratory switch device, a permanent armature electrically connecting the poles of said magnet, and means associated with said permanent armature for varying the path of the magnetic field of the permanent magnet relative to the vibratory switch device in accordance with variations in direction of the supplied current.

3. In a device for rectifying electric currents, a circuit arranged for connection to a translating device, a vibratory member for opening and closing the circuit, a permanent magnet arranged to operate the vibratory member, a connecting device disposed to provide a path for the magnetic circuit between the poles of the magnet, a source for supplying alternating current to the circuit, and means energized from said source for neutralizing the effectiveness of the connect-

ing device as a path for the magnetic circuit of the magnet.

4. A device for rectifying electric currents, a circuit arranged for connection to the translating device, a switch for opening and closing the circuit, a permanent magnet arranged to operate the switch to close the circuit, means normally neutralizing the effectiveness of the magnet with respect to the switch, and means effectively associated with the circuit for rendering said neutralizing means ineffective and thereby rendering the magnet effective upon the switch.

5. In a device for rectifying electric currents, a circuit arranged for electrical association with a translating device and a source of supply, a switch for opening and closing said circuit, a permanent magnet arranged for effective coöperation with the switch, there being a metallic connection between the poles of the magnet to complete a metallic path for the magnetic circuit, and a coil arranged to be energized from the same source with the circuit and inductively associated with said metallic connection.

In testimony whereof I hereunto affix my signature in the presence of a witness, this 14th day of August, 1916.

ALBERT WEHMEIER.
